UNITED STATES PATENT OFFICE.

LOUIS HOPPE, OF DOON, IOWA

GASOLENE-ENGINE.

1,047,228.

Specification of Letters Patent. Patented Dec. 17, 1912.

Application filed March 22, 1912. Serial No. 685,604.

To all whom it may concern:

Be it known that I, LOUIS HOPPE, a citizen of the United States, residing at Doon, in the county of Lyon and State of Iowa, have invented certain new and useful Improvements in Gasolene-Engines; and I do hereby declare the following to be a full, clear, and exact description of the invention, such as will enable others skilled in the art 10 to which it appertains to make and use the same.

This invention relates to internal combustion engines, such as gasoline engines; and it consists in the novel construction and 15 combination of the parts hereinafter fully described and claimed whereby the inlet valve is held closed by spring pressure when the exhaust valve is held open to permit the engine to run inactive, which is occasionally desirable. When running in this 20 manner the engine piston is reciprocated by the energy stored in the fly-wheel, and no power is developed in the cylinder, which is empty, the supply of fuel being cut off by 25 the speed governor.

In the drawings, Figure 1 is a sectional plan view of a portion of the cylinder of a gasoline engine provided with a spring-controlled lever for holding the inlet valve 30 closed according to this invention. Fig. 2 is a side view of the lever and its supporting bracket.

The power cylinder 2 of the gasoline engine is provided with an exhaust valve 3 having a spring 4 arranged around its stem 5, and adapted to close the valve. The inlet valve 6 has a stem 7, and a spring 8 which normally closes the valve and which 35 permits it to open automatically at intervals, to supply the cylinder with a charge of combustible fluid. The spring 8 is arranged in a spring chamber 9, between the end of the cylinder and a collar 10 secured 40 on the end portion of the stem 7. The chamber 9 has a slot 11 in one side of it.

A longitudinally slideable valve-rod 14 is provided, and this rod works back and forth in a guide 15 under the control of a speed governor of any approved make. The rear 50 end of the rod 14 is pivoted by a pin 16 to one end of a lever 17. This lever is pivoted by a pin 18 to the chamber 9, and its other end is arranged in operative connection with the stem 5 of the exhaust valve.

55 When the rod 14 is moved rearwardly, and is held by the governor in that posi-

tion, the exhaust valve is held open, so that the engine runs empty until its speed is reduced sufficiently to cause the governor to release the rod 14. Any approved detent mechanism may be used for holding the exhaust valve open, such as a pivoted pawl 30 carried by the engine frame and controlled by the speed governor, and engaging with a stop 31 on the rod 14. When the engine is running empty in this manner it is desirable that no combustible fluid be wasted by being drawn through the inlet valve, and the rod 14 is provided with a bell-crank lever 20 for holding the inlet valve closed when the exhaust valve is held open. The long arm of this lever is arranged to project through the slot 11 and come in contact with the collar 10.

The bell-crank lever is pivoted by a pin 21 to a bracket 22, which bracket is secured to the rod 14 by one or more bolts 23. This bracket has a slot 24 for the bolt 23, which permits it to be adjusted longitudinally of the rod 14. The short arm 25 of the bell-crank lever forms a stop which bears on the rod 14 to the rear of the pivot 21, and 26 is a spring arranged between the rod 14 and the long arm of the bell-crank lever to hold the long arm of the lever at substantially a right angle to the rod.

When the exhaust valve is opened by the rod 14, the long arm of the bell-crank lever engages with the collar on the stem of the inlet valve, and prevents the inlet valve from opening. The spring 26 enables the bell-crank lever to hold the inlet valve closed irrespective of the exact amount of the opening of the exhaust valve, and prevents injury to the various moving parts. The bell-crank lever is adjusted to close the inlet valve at the most advantageous moment by adjusting the position of the bracket 22 on the valve-rod.

What I claim is:

1. In an internal combustion engine, the combination, with a cylinder provided with an exhaust valve and a spring-controlled inlet valve, of a longitudinally slideable valve-rod, a pivoted lever connecting the said rod with the exhaust valve, a lever pivoted to the valve-rod and operating to hold the inlet valve closed when the exhaust valve is held open by the valve-rod, and a spring secured between the valve-rod and the last 105 said lever so that the inlet valve is held closed by spring pressure.

2. In an internal combustion engine, the combination, with a cylinder provided with an exhaust valve and a spring-controlled inlet valve, of a longitudinally slideable valve-rod, a pivoted lever connecting the said rod with the exhaust valve, a bell-crank lever pivoted to the valve-rod, one arm of the bell-crank lever being arranged to hold the inlet valve closed when the exhaust valve is held open by the valve-rod, and its other arm being arranged to operate as a stop, and

a spring arranged between the bell-crank lever and the said valve-rod and normally holding the said stop against the said rod, so that the inlet valve is held closed by 15 spring pressure.

In testimony whereof I have affixed my signature in the presence of two witnesses.

LOUIS HOPPE.
